UNITED STATES PATENT OFFICE.

ALONZO C. MATHER, OF CHICAGO, ILLINOIS.

COMBINED METALLIC DRAFT-SILL AND BODY-BOLSTER.

1,317,521.

Specification of Letters Patent. Patented Sept. 30, 1919.

Substitute for application Serial No. 828,169, filed March 30, 1914. This application filed December 20, 1916.
Serial No. 138,137.

To all whom it may concern:

Be it known that I, ALONZO C. MATHER, a citizen of the United States, residing at Chicago, in the county of Cook and State of Illinois, have invented a new and useful Combined Metallic Draft-Sill and Body-Bolster, of which the following is a specification.

My invention relates to draft sills and body bolsters for cars and particularly for freight cars known as long draft timber construction, and the objects of my improvements are first, to make the draft sills and body bolsters of removable sections or parts; second, to make the draft sills and bolster of metal and arrange the draft sills to have them replace the usual wood draft sills; third, to make the draft sills fit either wood or metallic sub-sills or beams; fourth, to make a strong durable and efficient construction and other features to become apparent from the description to follow.

In the upkeep of freight cars it becomes necessary to renew different parts and there is an ever increasing tendency to replace parts made of wood with parts made of metal. In what is known to the art as long draft timber cars, the draft timbers extend substantially the entire length of the car, i. e., beyond and between the upper and lower members of the iron body bolsters near each end of the car, and my improved draft sills are so arranged that they can be substituted in place of the wooden draft timbers, passing between the upper and lower members of the iron body bolster; and furthermore the ends of my improved draft sills are constructed so as to properly coöperate with either wooden draft timber sub-sills or metallic beams substituted in place thereof. By this means the wooden draft sill portion may be substituted by the metallic construction or both the draft sills and the long sub-sills may be substituted by metallic construction.

A further object of my improvement is to connect the draft sills to the body bolster so that it is very rigid and strong and so that the parts can be disconnected in sections when necessary without removing the greater part of the under construction of the car.

To describe my invention so that others versed in the art to which it pertains can make and use the same, I have illustrated

it on the accompanying two sheets of drawings forming a part of this specification, and in which:

Figure 1, is a plan view of the under construction of a car having my invention applied thereto with the main center sills removed; Fig. 2, is a sectional view taken on line 2—2 of Fig. 1, but showing wood sub-sills instead of I-beams; Fig. 3, is a sectional view taken on line 3—3 of Fig. 1, with parts in elevation; Figs. 4 and 5, are detail views showing a plan and a side elevation respectively of the king bolt or filler casting shown in Figs. 1 and 3; Fig. 6, is a detail plan view of one draft sill shown in Figs. 1, 2 and 3; Figs. 7, 8, 9 and 10, are cross sections taken on the correspondingly numbered lines of Fig. 6, respectively, viewed in the direction indicated by the arrows, and Fig. 11, is a plan view on a small scale showing the iron body bolsters near each end of the car and the manner of their coöperation between the ends of the draft sills and the sub-sills of the car.

Similar reference characters refer to similar parts throughout the several views.

The draft sills comprise two counterpart arms 12 between the one end of which the drawbar 13 and the usual draft gear mechanism is situated; the remaining ends of the draft sills 12 are provided with two extending flat bars 14 parallel and spaced apart sufficiently to straddle the web of an I-beam 15 as indicated by dotted lines in Fig. 10. The extremities of the flat bars 14 are bent at right angles in opposite directions to form an abutment 16 against which the ends of the wood sub-sills 17 rest and thus carry the shock exerted at one end of the car to the other end of the car. It will be noted that the sub-sills 17 extend from the draft sills at one end of the car to the draft sills at the other end of the car as shown in Fig. 11, no matter if the sill is formed of wood or of an I-beam. As viewed in said Fig. 11, the sills 17 are shown as of wood and in Fig. 1, the sills are shown as metal. When the sills 17 are formed of I-beams their ends are secured to the draft sills 12 by passing the central web of the I-beam between the bars 14 and by suitable bolts being secured in the holes 18 provided in the flat bars 14 integral with the arms 12; said bolts obviously pass through registering holes in the web of the I-beam.

The counterpart arms 12 are also provided with the depressions 19 in their opposed sides in which the usual follower plates 20 are arranged to play. The follower plates 20 are retained in position in the depressions 19 by suitable bars 21 bolted to the under side of each arm 12. The usual springs 22 are interposed between the follower plates 20, and the said plates 20 and springs 22 are 10 confined within the yoke 23 and the end of the drawbar 13 in the usual way. The arms 12 are located directly under the main car sills 24 and also extend under the end sills 25 and the dead wood 26. The dead wood 26 15 is preferably provided with the protecting channel iron 27 and the iron plate 28 to reinforce the same. The plate 28 rests against a shoulder or offset 29 formed on the arms 12. The arms 12 are securely bolted 20 to the sills 24 and 25 and also to the dead wood 26. To form additional rigidity between the arms 12 and the sills 24, the arms 12 are provided with transverse ribs 30 which fit into coöoperating notches 31 pro- 25 vided in the sills 24 as clearly shown in Figs. 1 and 2. The arms 12 each comprise the upper and lower horizontally disposed flanges 32 and 33 and the connecting vertically disposed web 34 as clearly shown in 30 Figs. 7, 8 and 9.

The car body bolster 35 employed in connection with the draft sills above described is preferably composed of the upper member 36, the lower member 37 and the metal fillers 38 which are secured between said two members on either side of the drawbar. The lower member 37 has its ends bent up on an incline on each side of the drawbar, to have its ends meet the ends of the upper member 40 36 as usual. At the central portion of the bolster 35 the upper and lower members 36 and 37 are sufficiently spaced apart to have the draft sills fit between them, and at the intersection of the longitudinal center line 45 of the bolster and the longitudinal center line of the drawbar a king bolt or filler casting 39 is securely bolted between the arms 12 by means of the bolts 40 or other suitable fastenings. The king bolt or filler casting 50 39 is provided with the vertically disposed king-bolt hole 41 through which the king-bolt passes to connect with the car truck. The fillers 38 of the bolster 35 are securely fastened in position by means of the bolts 55 42, which bolts serve to secure the members

36 and 37 together and also secure the bolster to the car sills.

The king bolt or filler casting 39, it will be noted by viewing Figs. 1, 2 and 3, is centrally disposed of the bolster 35 with its ends 60 fitting into the channel of the arms 12 and against the vertical web 34 thereof; and the bolster fillers 38 fit against the opposite sides of the said webs 34 of the arms 12, so that the bolts 40 serve to rigidly but removably 65 secure the filler casting 39, the arms 12 and the bolster fillers 38 together.

It will be noted that the several parts comprising the draft sills and the several parts comprising the body bolster are rigidly secured together, and to the car framing by means of screw bolts so that any of the parts can be removed or replaced. The usual longitudinal car trusses are shown at 43. 75

Having thus fully described my invention what I claim as new and desire to secure by Letters Patent of the United States is:—

1. In a device of the class described, a 80 pair of contraposed arms each comprising upper and lower horizontal flanges and a vertical web connecting said two horizontal flanges, said vertical web arranged along one edge of each of said horizontal flanges a 85 portion of the way and along the opposite edge a portion of the way and crossing from the one side to the other side on a diagonal line.

2. In a device of the class described, a 90 pair of contraposed arms each provided with a rectangular well or depressed portion, a king bolt or filler casting between said arms with its ends resting in said wells or depressed portion of the arms and rigidly 95 secured therein, said arms provided with transverse depressions in their upper and lower sides, a bolster having upper and lower members resting in said depressions in the arms and suitable fillers between the upper 100 and lower bolster members resting against said arms and rigidly secured in position.

In testimony whereof I have signed my name to this specification in presence of two subscribing witnesses this 11th day of November, 1916, at Chicago, Ill. 105

ALONZO C. MATHER.
